UNITED STATES PATENT OFFICE.

CHARLES D. KING, OF BROOKLYN, NEW YORK.

PIVOT-JOINT.

No. 831,354.

Specification of Letters Patent.

Application filed December 4, 1905. Serial No. 290,104.

REISSUED
Patented Sept. 18, 1906.

To all whom it may concern:

Be it known that I, CHARLES D. KING, a citizen of the United States, and a resident of Brooklyn, in the county of Kings and State 5 of New York, have invented certain new and useful Improvements in Pivot-Joints, of which the following is a specification.

This invention relates to pivot-joints; and its object is to provide joints of this class 10 which can be more readily adjusted than those heretofore made, which will be less liable to breakage, and which will need a minimum of repairing.

The invention is applicable to a number of 15 articles, but is shown applied to mathematical instruments, such as compasses or dividers; but I do not limit myself to this application of the invention. Pivot-joints as commonly made for such instruments consist 20 of a forked handle containing a pair of screw-pivots impinging in depressions in the upper ends of the compass-legs, and the pivots are kept from turning by small set-screws bearing on the threads of the pivot-screws or by 25 lock-nuts. It is obvious that the set-screws will often ruin the threads of the pivots, and also they are often broken off and ruin the instruments. The lock-nuts when used are 30 unsatisfactory and imperfect in their action, frequently working loose, and requiring adjustment at inconvenient times.

My invention differs from others of the class named from the fact that the pivots and their adjusting means are made as separate 35 members, and by that separation it is possible to positively lock the pivots against rotative movement relative to their supports when the instrument is opened and closed, and thus to make it impossible to turn the 40 adjusting-screws the smallest fraction of a turn by such action. This makes the adjustment very lasting and obviates the need of locking the adjusting screws or screw, (where only one is used,) so that readjustment is made by a slight turning of these 45 screws.

Referring to the drawings, Figure 1 is an enlarged side elevation, partly in section, on the center line of a compass or divider embodying my invention. Fig. 2 is a front elevation of the same. Figs. 3 and 4 are respectively side elevation and transverse section of the pivots drawn to a still larger scale. Figs. 5 and 6 are respectively front 55 elevation and longitudinal section of the adjusting-screws.

The instrument here illustrated has the usual divider-legs a a' , formed with disk-shaped upper ends b b' and a forked supporting member c , having a handle c' and projections c^2 c^3 to support the pivots d and adjusting-screws e and f .

Referring to Figs. 3 and 4, the pivots are seen to be formed with conical pivoting-surfaces d' , which bear in conical depressions a^2 , 65 formed in the ends of the divider-legs. They also have square-ended lugs or elongations d^2 , adapted to lock against the upper inside face c^4 of the pivot-supporting member c , and they have holes d^3 , which fit the pin or elongation of the screw e .

The adjusting-screws e and f are short headless screws of fine pitch, having the usual slots for turning them. The screw e has an elongation e' , smaller in diameter than the 75 threaded portion, which fits the holes d^3 in the pivots and also passes freely through holes a^3 in the divider-legs a a' and enters the hole f' in the screw f when the various parts are assembled. The hole f' extends nearly 80 through the screw f , so that a small clearance is left between the end of the pin e' and the end of the hole when both are in place in the instrument, thus allowing for such adjustment as becomes necessary through wear on 85 the pivots.

To assemble the various parts of the instrument, the legs a a' are placed together, while the pivots d d' are placed in the depressions a^2 , the fork c is slipped over them, and 90 the screws e and f are placed in their respective holes in the fork c , the pin e' serving to bring the pivots in line with each other and with the other screw f , after which the screws are given their final adjustment to bring the 95 pivots against the divider-legs with sufficient pressure to secure easy and accurate working of the instrument. Adjustment is made afterward as the pivoting-surfaces wear off by turning one or other of the screws a very 100 slight amount, and they remain positively in such adjustment, as there is nothing to give unintentional turning of the adjusting-screws. For turning the screws a screw-driver is preferred; but they may also be adapted for 105 wrenches of suitable construction.

If desired, the adjusting-screw f may be omitted from the instrument, and in such a modification it would be necessary to have the pin e' fit an unthreaded hole in the projection c^3 to bring the pivots into proper alinement.

Various other modifications may be devised within the scope of my invention, and I do not limit myself to one particular form.

I claim as my invention—

- 5 1. A pivot-joint for relatively movable members, comprising a suitable support, pivoting means within said support having integral locking means, juncture portions on the relatively movable members also disposed within said support and pivoted by said pivoting means, means for holding the pivoting means and the said juncture portions to the support, and means for adjusting said pivoting means and said juncture portions in position.
- 15 2. A pivot-joint for relatively movable members, comprising a suitable support, a pivot having integral means for locking it against rotative movement, juncture portions of relatively movable members connectable therewith, and means for holding said juncture portions and pivot to the support and adjusting them in proper position.
- 20 3. A pivot-joint for relatively movable members, comprising a forked support, pivotal portions of relatively movable members projecting into the fork thereof, self-locking

pivots on opposite sides of said pivotal portions within said fork, and means for holding and adjusting said pivotal portions and said pivots in their respective positions in the support.

4. A pivot compass-joint comprising a yoke, self-locking pivots carried therein, pivotal portions of compass-legs pivoted by said pivots, and means for alining and holding the pivots and pivotal portions of the legs to the yoke and adjusting them in position.

5. A pivot compass-joint comprising a forked support, pivots carried therein having lugs locking with said support to prevent rotation of the pivots, pivotal portions of compass-legs pivoted by said pivots, screws for adjusting said pivots, and a central member for alining the pivots and the pivotal portions of the legs with the support.

Signed at New York, in the county of New York and State of New York, this 24th day of November, A. D. 1905.

CHARLES D. KING.
